UNITED STATES PATENT OFFICE.

JOSEPH D. KING AND MATTHEW A. BURNS, OF MENOMINEE, MICHIGAN.

ADJUSTABLE HANDLE-BAR.

SPECIFICATION forming part of Letters Patent No. 613,683, dated November 1, 1898.

Application filed November 28, 1897. Serial No. 659,626. (No model.)

To all whom it may concern:

Be it known that we, JOSEPH D. KING and MATTHEW A. BURNS, citizens of the United States, residing at Menominee, in the county 5 of Menominee and State of Michigan, have invented certain new and useful Improvements in Adjustable Handle-Bars; and we do hereby declare the following to be a full, clear, and exact description of the invention, such 10 as will enable others skilled in the art to which it appertains to make and use the same.

Our invention relates to improvements in handle-bars for bicycles, and has for its object to provide a handle-bar that may be adjusted either vertically or horizontally by the 15 rider in an instant and, if desired, while the bicycle is in motion and without dismounting.

Our invention, which consists of the novel 20 devices and combination of parts hereinafter described and claimed, will be understood by reference to the accompanying drawings, wherein the same parts are indicated by the same letters throughout the several views.

25 Figure 1 represents a rear elevation of the handle-bar detached from a bicycle. Fig. 2 represents an enlarged central vertical section of the middle portion of the handle-bar and its post or "stem," taken on the line 2 2 2 in Fig. 4 and illustrating the interior mechanism. Fig. 3 represents a sectional view of the left-hand branch of the handle-bar, showing the arrangement of the trigger and chain for operating the devices for unlocking the 30 clutch. Fig. 4 represents a section taken on the line 4 4 in Fig. 2. Fig. 5 represents a detail plan view, parts being broken away, of the joint in the handle-bar. Fig. 6 represents a detail view of the adjustable connection for the trigger shown in Fig. 3, and Fig. 7 is a diagrammatic view illustrating the 35 possibilities of adjustment that may be given to the handle-bar by means of our improved mechanism.

40 A represents the handle-bar, and B represents the handle-bar post or stem.

The handle-bar is made of hollow tubing and is composed of two sections—a right-hand section A' and a left-hand section A². The 45 two sections are joined together by means of a screw-collar A⁰, which turns freely in a groove a² on the left-hand section A² and en-

gages screw-threads a' on the end of the right-hand section A', as seen most clearly in Figs. 2 and 5. The adjacent ends of the two sections of the handle-bar are provided with interlocking teeth, as seen at a⁴ in Fig. 5, to prevent the turning of one section relative to the other, as will be obvious. The section A' has a clutch A³ formed integral therewith and 55 provided with teeth A⁵ upon one face thereof, as seen most clearly in Figs. 2 and 5.

The handle-bar post or stem B is made hollow, and has its lower portion B' turned down to a smaller diameter to fit into a hollow inclosing sleeve B⁰, as seen in Figs. 2 and 4. The said stem is provided with a pair of opposite vertical slots b⁰ b⁰, which extend from near its upper end down into the lower portion B', as shown at b' b' in Figs. 2 and 4. 60 The inclosing sleeve B⁰ is also provided with a pair of opposite slots b² b². (Indicated in dotted lines in Figs. 2 and 4.) The reduced portion B' of the stem B turns freely in the sleeve B⁰, so that the slots b² b² in the said 65 sleeve may be turned into and out of coincidence with the slots b⁰ b⁰ in the said stem, as 70 will be hereinafter more fully described.

A block C, having a larger portion c, which 75 works in the upper portions of the slots b⁰ b⁰ and also in the slots b² b² in said sleeve, is mounted in said slots b⁰ b⁰ and has a reduced portion c', which works in the lower portions b' b' of said slots in the stem B'. The said block C is provided with a pair of opposite-curved 80 arms or triggers C² C², by means of which the said block may be raised for the purpose of disengaging the portion c from the slots in the said sleeve B⁰, and thus allowing the stem to 85 turn in said sleeve. The block C is held normally locked in the slots of the said sleeve B⁰ by means of a coil-spring D, which is connected at one end to a perforated lug c⁰ on the bottom end of the said block C and is connected at its other end to a screw D', which 90 latter is engaged by an adjusting-nut D⁰ for regulating the tension on the spring D. A hollow screw-plug E engages in the end of the lower portion B' of the stem and has a flanged head e, which holds the sleeve B⁰ upon the 95 said lower portion of the stem, as seen in Fig. 2. The screw D' passes freely through this hollow screw-plug E, as will also be seen by an inspection of Fig. 2.

The stem B has a collar B² formed integral with its upper end, through which collar may pass the end of the section A' of the handle-bar, and this collar is recessed at one side, as seen at b⁴ in Fig. 2, and is provided with clutch-teeth b⁵, adapted to interlock with the teeth a⁵ on the clutch A³, which latter fits into the recess b⁴ in the collar B², as seen in Figs. 2 and 5. The section A' of the handle-bar may move laterally through the collar B² just far enough to allow the teeth a⁵ on the former to become disengaged from the teeth b⁵ on the latter, the said lateral movement being limited by the connecting screw-collar A⁰, hereinbefore described. In order to hold these two sets of clutch-teeth in engagement with each other and so lock the handle-bar against turning, a coil-spring F is fitted within the handle-bar and is confined at one end by means of a fixed annular rib or collar f, while at its other end it bears against a sliding sleeve F', through which latter passes a diametrical pin f', which passes at its ends through slots a⁶ a⁶ in the section A' of the handle-bar and engages at its ends in an annular groove b⁶ in the interior of the collar B². In this manner the handle-bar is held locked against turning in the collar B², but for the purposes of unlocking the said handle-bar in order to turn the same we have provided the following means:

A chain H is connected at one end to the pin f' and passes through the interior of the section A' of the handle-bar to a point in proximity to the hand-grip on that section, where it is connected to a pivoted lever or trigger H' by means of an adjustable frame H², as seen in Fig. 3. The lever or trigger H' is pivoted within an inclosing lug h⁰ beneath the handle-bar and passes through slots h² and h³ in the tubing of the handle-bar, being provided at its upper end with a thumb-piece h', by which it may be operated by the thumb of the rider. The frame H², by means of which the chain is connected to the said lever or trigger, is capable of adjustment as required by means of the screw-bolt h⁴, to which latter access may be had by removing the hand-grip I, as will be obvious.

It will be seen that the pull on the chain H will be communicated through the pin f' to the rigid collar B², which, being fixed to the bicycle-frame, will not move, but will simply serve as an anchor for the chain H, which, serving as a fulcrum for the lever or trigger H', will cause the whole handle-bar to move transversely, and thus disengage the clutch-teeth. Upon releasing the trigger H' the coil-spring F will throw the handle-bar back again into engagement with the collar B², by which it will be locked against turning.

In use upon a bicycle the sleeve B⁰, inclosing the lower portion B' of the stem B, is clamped in the steering-head of the bicycle in the usual manner, and in order to reverse the handle-bar—that is to say, in order to convert the handle-bar from a position having

an upward curve, as seen in full lines in Fig. 7, to a position having a downward curve, as seen in dotted lines in said figure, or vice versa—by pulling up on the triggers or arms C² C² the block C will become disengaged from the slots in the said sleeve, and the said stem may then be turned through an angle of one hundred and eighty degrees, thus reversing the handle-bar, which may then be given the desired inclination by releasing the clutch hereinbefore described and turning the bar through a vertical plane to the desired position, as will be readily understood by any practical mind. We do not, however, wish to limit ourselves to the precise details of construction hereinbefore described, and shown in the accompanying drawings, as many modifications might be made in such details which could be used without departing from the spirit of our invention.

Having thus described our invention, what we claim, and desire to secure by Letters Patent of the United States, is—

1. In a handle-bar for bicycles, the combination with the horizontal bar; of a hollow stem adjustable about said bar; a sleeve loosely inclosing a reduced portion of the lower end of said stem, and adapted to fit into and be clamped within the steering-head of the bicycle; a screw-plug engaging within the lower end of said hollow stem; and a hand-operated locking-latch working in a radial slot in said stem, controlled by a spring within said stem, normally locking said stem against turning in said sleeve, substantially as described.

2. In a handle-bar for bicycles, the combination with the horizontal bar; of a hollow stem adjustable about said bar, and having a pair of oppositely-disposed radial slots therethrough; a sleeve loosely inclosing said stem and adapted to fit within and be clamped within the steering-head of the bicycle, said sleeve having notches in one end adapted to coincide with the said radial slots in said stem; a screw-plug engaging within the lower end of said hollow stem, and having an axial opening therethrough, and an enlarged head confining said sleeve upon said stem; a latch-block fitting in the radial slots in said stem, and capable of axial movement therein, having a narrower portion working in said sleeve, and having a wider portion adapted to engage in said notches in the end of said sleeve; a coil-spring connecting to said latch-block within said hollow stem; and a tension-bolt to which said coil-spring is also connected, passing through the axial opening of said plug, and engaged by a nut; and laterally-extending ears on said latch-block whereby the latter may be disengaged from the notches in said sleeve, substantially as described.

3. In a handle-bar for bicycles, the combination with the stem having a cylindrical collar upon its upper end provided with a clutch-face upon one side; of a hollow horizontal bar composed of a longer and a shorter section

connected by a screw-collar, the longer section of said bar passing through the collar on said stem and having a clutch-face rigidly fixed thereon adapted to engage the clutch-face of said cylindrical collar; a fixed stop within the shorter section of said bar; a sliding sleeve within the longer section of said bar, a diametrical pin passing through said sleeve and through axial slots in said longer section of the bar, and engaging in an annular groove in the said cylindrical collar on said stem; a coil-spring interposed under compression between said fixed stop within the shorter section of said bar and said sliding sleeve within

the longer section thereof; a trigger pivoted 15 diametrically of said shorter section of the bar; an adjustable frame engaging said trigger within said bar; and a flexible connection between said adjustable frame and said diametrical pin, substantially as described. 20

In testimony whereof we affix our signatures in presence of two witnesses.

JOSEPH D. KING.
MATTHEW A. BURNS.
